Arthur B. Denkins
ATTORNEY

UNITED STATES PATENT OFFICE.

JOHN J. THACHER, OF WETHERSFIELD, CONNECTICUT.

SHAFT BEARING.

Application filed February 15, 1923. Serial No. 619,263.

To all whom it may concern:

Be it known that I, JOHN J. THACHER, a citizen of the United States, and a resident of Wethersfield, in the county of Hartford and State of Connecticut, have invented new and Improved Shaft Bearings, of which the following is a specification.

My invention relates to the class of devices commonly employed for supporting 10 rotating elements, as shafting, and an object of my invention, among others, is the provision of a bearing capable of producing most efficient results in the matters of lubrication and of durability.

One form of device embodying my invention and in the construction and use of which the objects herein set out, as well as others, may be attained, is illustrated in the accompanying drawings, in which—

20 Figure 1 is a view of my improved bearing just before being turned to annular form.

Figure 2 is a side view of the complete bearing.

25 Figure 3 is a view of a portion of a strip cut from a piece of timber and from which the blocks composing the bearing are produced, the shape of the blocks being shown by dotted lines.

30 Figure 4 is a diagrammatic view illustrating the manner in which the strip from which the blocks are produced is cut from a piece of timber.

Figure 5 is a detail view illustrating the 35 case and my improved bearing partially inserted therein.

I have demonstrated to my satisfaction that a bearing of the type herein contemplated and composed of wood, if constructed 40 to dispose the grain of the wood in a predetermined manner, will secure the most efficient results. These results will be attained, according to my present invention, by so forming the bearing that the laminations produced by each successive year's growth of the wood shall be placed with their side edges forming the interior of the bearing, and by side edges I mean the edges that are produced when a cut is made 45 through a piece of timber lengthwise thereof substantially on a radial line.

It is common in the construction of bearings of this type to saturate such bearings with oil, the oil being retained between the 50 laminations or layers of the wood, and by disposing these laminations as above de-

scribed the bearing will be adapted for the supply of oil to its interior to a maximum extent, and, moreover, by forming the bearing as above described a structure of maximum strength is obtained.

In constructing a bearing according to my present invention I cut a piece 6 from a stick of timber 7, as illustrated in Figure 4, the location of the piece 6 being shown in dotted lines in said Figure 4. This piece 6 is then cut into blocks 8 as illustrated by the dotted lines in Figure 3, and it will be noted that the laminations 9 produced by each successive year's growth of the timber will extend across the blocks so that the side edges 10 of such laminations will be on the interior of the blocks when secured together, as shown in Figure 1. In order to provide the structure, as shown in said Figure 1, the blocks are cut on planes 11 running diagonally to the sides of the piece 6. These blocks are then secured together as by an adhesive, and as shown in Figure 1, the diagonal cuts producing miter joints 12. The structure is then cut to annular form to produce the bearing 13, as shown in Figure 2, the opening through the bearing being of a size to provide a running fit for the shaft or like device to be supported within the bearing.

In the use of bearings for shafting a pull or force is usually exerted in a certain direction owing to the strain caused by belts passing over pulleys mounted upon the shafting; and it is practically impossible, in installing a bearing, to anticipate the direction in which these strains will be exerted, owing to the fact that belts will extend in different directions, and it would, therefore, be practically impossible to tell in which direction the greater forces will be exerted. Further than this, owing to changes in such belting, the direction of the forces upon the shafting will be changed from time to time.

It, therefore, becomes important to provide a bearing that will meet this condition irrespective of the direction in which the forces may be exerted. In providing my improved bearing as illustrated and described herein, I have met this problem by so arranging the blocks with the laminations thereof disposed in a certain way whereby the resistance of the bearing to forces applied to shafting supported by the bearing will be substantially the same in all direc-

tions, and by cutting the blocks so that the grains and laminations will be disposed as herein set forth a bearing capable of resisting such forces to a maximum degree 5 and without fracture is produced.

I am aware that wood has heretofore been employed in the construction of bearings and I do not broadly claim such a structure herein, but, so far as I am aware, it has 10 never heretofore been proposed to construct a bearing of wood with the laminations and grains so arranged that the side edges of the laminations and grains of wood will be in contact with the rotating elements, 15 as illustrated and described herein. It will be understood that a bearing of this type is inclosed within a metallic case or sleeve 14, the latter being commonly mounted to turn on an axis extending laterally of the 20 axis of said sleeve. In order to obtain the best results the bearing 13 is driven into the sleeve or case, and it will be seen that a bearing constructed as herein set forth has the

grain so disposed as to enable this driving operation to take place with little liability 25 of breaking the bearing, the force created by the blows being resisted by the bearing in a direction lengthwise of the grain thereof.

I claim—

1. A bearing formed of a plurality of 30 pieces of wood transversely cut from a block of wood having the grain running lengthwise thereof with the several blocks having the grain running transversely, said blocks being beveled at their ends and secured together in end to end relation to form a tubular structure and said structure being turned to form an annular bearing with the grain of the bearing extending 35 radially thereof.

2. A bearing formed of a plurality of pieces of wood of segment formation, said bearing being of annular formation with the grain of the several segments radiating directly from the axis of the bearing.

JOHN J. THACHER.
